US00D543191S

(12) **United States Design Patent** (10) **Patent No.:** **US D543,191 S**
Kim et al. (45) **Date of Patent:** **** May 22, 2007**

(54) **PORTABLE PHONE**

(75) Inventors: **Jin-Soo Kim**, Yongin-si (KR); **Nam-Mi Kim**, Seoul (KR); **Chang-Hwan Hwang**, Goyang-si (KR)

(73) Assignee: **Samsung Electronics Co., Ltd.**, Suwon-Si (KR)

(**) Term: **14 Years**

(21) Appl. No.: **29/257,562**

(22) Filed: **Apr. 7, 2006**

(30) **Foreign Application Priority Data**

Oct. 28, 2005 (KR) 30-2005-0036452

(51) **LOC (8) Cl.** **14-03**

(52) **U.S. Cl.** **D14/138**

(58) **Field of Classification Search** D14/137, D14/138, 147, 218, 341-347; 455/90.3, 556.1, 455/556.2, 575.1, 575.3, 575.4; 379/433.01-433.13; 361/814; 348/14.02

See application file for complete search history.
